PRINTING MEANS FOR LABELING MACHINES

Hans A. Nefzger, Hackensack, N. J., assignor to New Jersey Machine Corporation, Hoboken, N. J., a corporation of New Jersey

Application August 15, 1951, Serial No. 241,989

6 Claims. (Cl. 101—318)

This invention relates to labeling machines and more particularly to labeling machines provided with means for imprinting the labels at a predetermined period in the operative cycle of the machine.

The principal object of the invention is to provide in such a machine an improved printing means which will enable the application of the printed material to any selected part of a label and which will give more uniform and better printing results.

Other objects of the invention, as well as the novel features of construction thereof, will become apparent from a perusal of the following description, when read in connection with the accompanying drawings, in which Fig. 1 is a fragmentary elevational view of a machine embodying the invention; Fig. 2 is a perspective view showing the mechanism for adjusting the printing means relative to the label stack; Fig. 3 is a side elevational view on an enlarged scale of the printing head or unit; Fig. 4 is a fragmentary side elevational view, partly in section, and showing the arrangement of the label control parts when the label carrying means is in position to pick up a label from the stack; Fig. 5 is a view similar to Fig. 4 and showing the relation of such parts just after the label carrying means has withdrawn a label from the stack; and Fig. 6 is a sectional view taken along the line 6—6 of Fig. 2.

The invention is illustrated with respect to a well known form of labeling machine provided with a suitable hopper 10 in which is contained a supply of labels 11 in stacked arrangement with the printed faces disposed upwardly. The labels 11 may be provided with a coating of thermo-activatable adhesive material or may be plain labels to which is applied a coating of suitable adhesive material in their travel from the hopper 10 to the articles to which they are to be applied. Machines of this type usually include also an automatically controlled mechanism for elevating the stack of labels 11 at intervals to thereby periodically restore the upper end of the stack to a predetermined level. This elevating mechanism and its control means may be of any conventional form and arrangement. In the type of machine illustrated, the means whereby the elevating mechanism is controlled includes a controlling member 12 carried by a slide 13 vertically movable in a stationary guide 14, and connected by means of a link 15 with the operating means, whereby the member 12 is vertically reciprocated in predetermined timed relation with the other operating elements of the machine, such operating means in conventional existing arrangements including a suitably shaped cam for producing the vertical reciprocation of the member 12. In prior machines of this type, the member 12 acts as a feeler adapted during each downward movement in the vertical reciprocation thereof to engage the upper end of the stack of labels 11. As the height of the stack decreases because of the progressive removal of labels therefrom, the downward movements of the member 12 correspondingly increase in extent, so that finally the feeler 12 brings about an operation of the elevating mechanism whereby the

2

upper end of the stack of labels is periodically restored to a predetermined level. Unlike such prior constructions, however, the member 12 in the instant construction does not accomplish its control by coming into contact with the uppermost layer in the stack, but attains its results by engaging the top of the printing means, as will hereinafter appear more clear.

In the selected form of labeling machine shown in the drawings, the labels 11 are removed in individual succession from the upper end of the stack by means of a suction head 16 carried by an open frame or yoke 17 which is supported by and vertically movable on a carriage 18. The latter is arranged to be reciprocated on a stationary rail 19 by suitable mechanism exemplified by the lever 20 and connecting rod 21 to carry each successive label 11 from the stack to the place of application at which the article to be labeled is supported in label receiving position in any well known way, as by the support 22. In the operation of such mechanism, the yoke or open frame 17 and the suction head 16 are lowered at one terminus of the reciprocation of the carriage 18 to cause the head 16 to pick up the terminal or uppermost label 11 in the stack and to raise such label therefrom; the raised suction head 16 with the lifted label thereon being then shifted with the carriage 18 along the rail 19 to the left, as viewed in Fig. 1 of the drawings, and to the aforesaid point of application. At this point, the yoke 17 and the suction head 16 are lowered to apply the label carried by the latter to the article on the support 22. It will be understood that the suction effective at the active surface of the suction head 16 is controlled in any conventional manner in proper synchronism with the aforesaid operative steps to produce the desired results. In its travel from the stack to the place of application, the label carried by the suction head 16 is rendered adhesive either by the use of heat, if it has a coating of thermoactivatable adhesive material, or by the application of a coating of any suitable adhesive material. During the travel of the suction head 16 from the stack to the place of application, means come into operation to apply printed material to the next succeeding label in the stack 11.

In accordance with the invention, the means for imprinting the labels include a sleeve 25 mounted for sliding, reciprocal movement on a vertically disposed fixed shaft 26 which is supported at its upper and lower ends by brackets 27, 28, secured to the frame 29 of the machine. Pivotally connected to a lug 30 provided on the lower end of sleeve 25, is the upper end of a link 31 whose lower end is pivotally connected to the outer free end of a lever 32. The lever 32 is pivotally supported at its other end by a bracket 33 mounted on the frame of the machine and is provided intermediate its ends with a cam roller 34 which rides on the periphery of a continuously rotating cam 35. The cam 35 is designed to reciprocate sleeve 25 on shaft 26 through roller 34, lever 32 and link 31 in synchronism with the movements of the suction head 16, so that when the latter operates to remove the terminal label from the stack, the sleeve 25 will be raised on the shaft 26, while when the carrier 18 with the suction head 16 is slidably moved toward the left in Fig. 1 of the drawings, the sleeve 25 will be permitted to return by gravity to a lowered position. A spring 36 connected at one end to the outer end of lever 32 and at its lower end to a lug 37 provided on the frame of the machine, serves to facilitate the downward movement of the sleeve 25 and to tend to maintain the cam rollers 34 in engagement with the cam 35. The lug 37 is provided with a number of apertures to which the spring 36 may be variably connected to vary the tension of the latter.

Mounted on a bracket 40 provided on the sleeve 25 is a vertically-disposed rectangularly-shaped guide plate 41 having a horizontally-disposed guide groove 42 and

having one end thereof projecting horizontally inwardly of the frame 29. Slidably received in the groove 42 for lengthwise movement relative to the latter, is a guide bar 43 having a longitudinally extending channel 44. The bar 43 is maintained in position in the groove 42 by means of a cover plate 45. Mounted on the lower horizontal shoulder formed by the groove 44 is a rack bar 44' with which is meshed a pinion 39 secured to a stem 46 extending through the cover plate 45. To the outer end of stem 46 is secured a knob or handwheel 47 by which the stem 46 and pinion 39 may be rotated to move rack 44' and consequently bar 43 lengthwise relative to the guide block composed of plates 41 and 45. It will be noted from Fig. 6 of the drawings, that the inner end of the stem 46 projects slightly beyond the pinion 39. The stem 46 is rotatably mounted in a bearing sleeve 38 which is threadedly engaged in the cover plate 45 so that it may be screwed or unscrewed to shift its position lengthwise with relation to such plate. The outer end of sleeve 38 is provided with a handwheel 38' by which the sleeve 38 may be normally rotated to adjust its position relative to plate 45. The inner end of sleeve 38 is adapted to engage with the hub of pinion 39 to force such pinion and the stem 46 inwardly to bring the projecting inner end of the latter into engagement with the inner wall of the groove 42 when the handwheel 38' is turned in one direction. When the handwheel 38' is turned in the opposite direction, the outer end thereof engages with the shank of the knob 47 to shift the pinion 39 and stem 46 outwardly to disengage the inner end of such stem from the inner wall of groove 42. It will thus be seen, that in an adjusted position of the bar 43, the handwheel 38' has been turned to cause the inner end of stem 46 to bear against the inner wall of groove 42, thus locking bar 43 in its adjusted position. When it is desired to adjust the position of bar 43 relative to the guide plate 41, the handwheel 38' is turned to withdraw the stem 46 from engagement with such bar and the bar is moved lengthwise in the guide block composed of plates 41 and 45 by turning the knob 47. When the proper adjustment of the bar 43 with relation to such guide block has been made, the handwheel 38' is again turned to fix it in such position by means of the stem 46.

The inner projecting end of bar 43 is provided with a vertically arranged guide plate 48 which is disposed at right angles to the longitudinal axis of bar 43 and like plate 41, is provided with a horizontal guide groove. Slidably mounted in the groove of plate 48 is a bar 49 having a longitudinally extending channel 50. Secured to the plate 48 is a cover plate 51; the two plates constituting a guide block for the bar 49. The bar 49 is adjustably moved and secured in an adjusted position relative to the guide block by means of mechanism similar in construction to that described with relation to bar 43 and illustrated in Fig. 6 of the drawings, it being believed sufficient in view of the description of the former to indicate the knob for shifting bar 49 by the numeral 52 and to indicate the handwheel for locking the bar 49 in an adjusted position by the numeral 53.

It will be noted that by reason of the above described method of mounting bars 43 and 49 on sleeve 25, one end of bar 49 will extend over the stack of labels 11. Mounted on such end of bar 49 is a block 54, which overlies the label stack 11 and whose position with relation to the terminal label in such stack may be varied by adjustment of the bars 43 and 49 in the manner previously described. Removably connected in any suitable fashion to the block 54 are a plurality of depending bars 55 provided at their lower ends with type or other equivalent means capable of imprinting the desired printed matter, such as code marks or numerals, on the labels 11. Positioned below the bars 55 is a pressure plate 56 provided with apertures through which the bars 55 may extend during the printing operation (note Fig. 3 of the drawings). The plate 56 is supported on the block 54 by a plurality of vertical rods 57 which are connected at their lower ends to

such plate and extend up through passageways in the block 54; the upper ends of such rods being provided with an enlargement such as the lock nuts 58 which engage the shoulders formed by the recesses 54' in which they are located to limit movement of such rods relative to the block in a downward direction. Mounted on the rods 57 between the block 54 and pressure plate 56 are springs 59 which normally maintain the plate 56 in an advanced position relative to the block 54, with the nuts 58 in engagement with the shoulders or inner walls of recesses 54', and which yieldingly resist movement of the plate 56 toward the block 54.

The inking pad 60 for the type on the bars 55 is mounted on the upper surface of the suction head 16. As is shown more clearly in Fig. 4 of the drawings, the pad 60 is mounted in a recess bounded by any suitable stop means, such as the walls 61 provided on the head 16, the upper surface of the inking pad being located below the upper edges of such stop means or walls 61. Thus, when the parts are in position to ink the type on bars 55, the plate 56 of the printing unit will be seated on the upper edges of the walls 61 and the bars 55 will be extended through such plate so that the type thereon will be in engagement with the inking pad 60, as is shown in Fig. 5 of the drawings.

From the foregoing description of the parts, it will be understood that in the operation of the machine, the printing unit is reciprocated in a vertical direction during the horizontal movements of the suction device 16, while the control member 12 feels the upper surface of the printing unit in its control of the stack of labels. Let it be assumed that the parts are at that period in the operative cycle of the machine just subsequent to the application of a label to an article, with the suction head 16 being raised on the carriage 18 to the position at which it will be returned to the stack of labels 11. As shown in Fig. 1 of the drawings, the block 54 at this time occupies a lowered position with the plate 56 pressing on the stack of labels 11 and the bars 55 advanced through such plate so as to imprint the uppermost label in the stack. The member 12 will also be in a lowered position in contact with the top surface of the bar 49 which is flush with the top surface of the block 54.

When the yoke 17 and suction head 16 have been raised to the proper point on the carriage 18, the latter is shifted lengthwise of the rail 19 toward the right, as viewed in Fig. 1, to bring the suction head over the stack of labels 11. In proper timing with this operation, the slide 13 is shifted upwardly in the guide 14 to raise the member 12 to a point at a distance above the stack of labels and such that when the suction head 16 is moved over the stack 11, such member will be removed from its path (note Figs. 4 and 5). The block 54 is also lifted by the sleeve 25 through its associated connecting bars and guide blocks to a raised position at which it will enter into the yoke 17 when the latter arrives over the stack 11, as shown in Fig. 4 of the drawings. During this upward movement of the block 54, the movement of the plate 56 thereon will be retarded by the springs 59, while the bars 55 are withdrawn therefrom and when the nuts 58 again engage the inner walls of the recesses 54' in the block 54, such block with the plate 56 will be raised as a unit.

When the suction head 16 is positioned over the stack 11, the yoke 17 is moved downwardly to bring such head into contact with the top of the stack of labels 11, as illustrated in Fig. 4 of the drawings. It will be noted that at this point in the cycle of operation, the inking pad 60 is directly below and in registry with the plate 56 and type bars 55 carried by the block or head 54. In properly timed relation, suction is made effective in the suction head 16, so that when the latter with yoke 17 is raised from the position shown in Fig. 4, the terminal or uppermost label in the stack is removed by such head 16. This upward movement of the suction head 16 is continued until the plate 56 seats on

the upper edges of the walls 61 and the type bars 55 advance through the apertures in such plate into engagement with the inking pad 60, as shown in Fig. 5 of the drawings. As a result of this, the type on the bars 55 are readied for the next printing operation.

When proper engagement has been established between the type bars 55 and the inking pad 60, the yoke 17 is given a slight downward movement on the carriage 18 to remove the pad 60 and walls 61 away from the type bars 55 and the plate 56, the springs 59 during such movement of the yoke moving the plate 56 relative to the type bars 55 until the latter have been withdrawn from a projecting position relative to such plate. The carriage 18 is then shifted along the rail 19 to the left, as viewed in Fig. 1 of the drawings, during which travel, the label is rendered adhesive either by the application of heat, if it is coated with thermo-activatable adhesive material or by the application thereto of a suitable adhesive if it is a plain label. When the carriage 18 reaches the end of its travel to the left, the yoke 17 is moved downwardly on the carriage 18 to cause the suction head 16 to apply the label carried thereby to the article mounted on the support 22 at the label application station. At the proper moment in this cycle of operations, the suction in the head 16 is released and the yoke 17 is moved upwardly relative to the carriage 18, leaving the label in adhesive connection with the article. The application of the applied label to the article is then completed in any customary manner and the labeled article is replaced at the place of application by another article to be labeled.

During the period in which the label carried by the suction head 16 is being transferred to the article and applied thereto, the sleeve 25 is moved downwardly on the shaft 26 under the tension of spring 36 in the manner previously explained to cause the block or head 54 to move downwardly toward the uppermost label in the stack 11. In the downward movement of the printing unit, the plate 56 will first engage the uppermost label. As the unit continues its downward movement the plate 56 will compress the stack under the increased pressure of the compressing springs 59 and cause the latter to become a solid base for the printing operation. During this pressing action of the plate 56, the head 54 continues to move downwardly, advancing the type bars 55 through the perforations of plate 56 against the pressure of springs 59 to bring the type on such bars into contact with the uppermost label in the stack. As a result of the solidified condition of the stack, the printing operation will take place under very advantageous conditions and will provide a cleaner and clearer result than is possible by imprinting on a stack not so solidified. By suitably adjusting the spring 36 to the bracket 37, the imprint made by the type may be controlled so as to be either light or heavy or in any intermediate shade. When adjusting this connection of spring 36, the force exerted by the springs 59 will of course, have to be taken into account. By reason of the two possible adjustments of the head 54 on the sleeve 25 with relation to the stack of labels, the particular portion of the label to be printed, can be determined with great exactness, which is of extreme importance in the printing of many labels where a relatively small space is provided for the application of code marks or other identifying indications. The range of movement of the sleeve 25 and consequently the printing unit is sufficient to allow for a predetermined depletion of the label stack without effecting the printing operation. In predetermined timing with the printing operation, the member 12 is moved downwardly to bring it into contact with the top surface of the bar 49 of the printing unit at the moment that the type bars 55 of the latter are applying the printed matter to the uppermost label in the stack 11. The member 12 in cooperation with the printing unit thus controls the operation of the stack

elevating mechanism. It will be observed that the feeler 12 is a flat plate of such dimensions that no matter to what position the head 54 has been adjusted relative to the uppermost label in the stack, such feeler will engage the upper surface of the bar 49 in its downward testing movement. This construction also has the advantage that a stack of labels may be indexed even though the labels in such stack have a smaller area than the pressure plate 56 of the printing unit. Thus, a stack of very small labels may be consolidated for proper printing and simultaneously indexed, which would otherwise be impossible of accomplishment with known mechanisms.

While I have described and illustrated a preferred form of my invention, it will be understood by those skilled in the art that various changes may be made therein without departing from the spirit of the invention or the scope of the appended claims.

I claim:

20. 1. In a labeling machine of the type which comprises a support for a stack of labels and constructed and arranged to be periodically actuated to restore the terminal label of the stack to a predetermined position and transfer means including a suction device for successively removing labels from such stack, the combination with said support and transfer means of a printing unit having a surface spaced from the terminal label in the stack, means for supporting said printing unit for reciprocal movement toward and away from the terminal label of the stack, means for reciprocating said supporting means to cause said printing unit to produce an imprint on the terminal label of the stack and to withdraw said printing unit prior to the removal of such terminal label by said transfer means, a feeler member 35 separate from said printing unit and intermittently engageable with said printing unit surface to control the actuation of said stack support and reciprocating means for bringing said feeler member into engagement with such surface every time and while said printing unit is 40 producing an imprint on the terminal label of the stack.

2. In a labeling machine of the type which comprises a support for a stack of labels and constructed and arranged to be periodically actuated to restore the terminal label of the stack to a predetermined position and transfer means including a suction device for successively removing labels from such stack, the combination with said support and transfer means of unitary means for periodically producing an imprint on the terminal label of the stack and having a surface spaced from such terminal label during the production of such imprint, unitary means for periodically engaging such surface of said imprinting means to test the position of said imprinting means during the printing operations of the latter to control the actuation of said stack support, and means 55 for reciprocating said imprinting means to produce an imprint on a terminal label and for reciprocating said testing means to engage said imprinting means each time the latter is producing an imprint, said reciprocating means being constructed and arranged to move said testing means into engagement with such surface of said imprinting means at the moment that the latter is producing an imprint on the terminal label of the stack.

3. In a labeling machine of the type which comprises a support for a stack of labels and constructed and arranged to be periodically actuated to restore the terminal label of the stack to a predetermined position and transfer means including a suction device for successively removing labels from such stack, the combination with said support and transfer means of unitary means for periodically producing an imprint on the terminal label of the stack and having a surface spaced from such terminal label during the production of such imprint, means operable to selectively adjust the printing position of said imprinting means relative to the terminal label 70 of the stack and consequently to shift the position of

such surface relative to such terminal label, unitary means movable along a predetermined path for periodically engaging such surface of said imprinting means to test the position of said imprinting means during the printing operations of the latter to control the actuation of said stack support, said testing means comprising a member having a surface engageable with the surface of said imprinting means and of such dimensions that whenever printing position said imprinting means has been adjusted, such surface will engage with the surface of said imprinting means during a printing operation, and means for reciprocating said imprinting means to produce an imprint on a terminal label and for reciprocating said testing means to engage said imprinting means each time the latter is producing an imprint, said reciprocating means being constructed and arranged to move said testing means into engagement with such surface of said imprinting means at the moment that the latter is producing an imprint on the terminal label of the stack.

4. In a labeling machine of the type which comprises a support for a stack of labels and constructed and arranged to be periodically actuated to restore the terminal label of the stack to a predetermined position, and transfer means including a suction device for successively removing labels from such stack, the combination with said support and transfer means of a printing unit having a surface spaced from the terminal label in the stack, means for supporting said printing unit for reciprocal movement toward and away from the terminal label of the stack, means for reciprocating said supporting means to cause said printing unit to produce an imprint on the terminal label of the stack and to withdraw said printing unit prior to the removal of such terminal label by said transfer means, said printing unit including a yieldable pressure plate for engaging the terminal label to consolidate the stack during the printing operation and a type carrier constructed and arranged to bring the type carried thereby into engagement with the terminal label within the area consolidated by said pressure plate, a feeler member separate from said printing unit and intermittently engageable with said printing unit surface to control the actuation of said stack support, and reciprocating means for bringing said feeler member into engagement with such surface every time and while said pressure plate and the type on said type carrier are in engagement with the terminal label of the consolidated stack.

5. In a labeling machine of the type which comprises a support for a stack of labels and constructed and ar-

ranged to be periodically actuated to restore the terminal label of the stack to a predetermined position, and transfer means including a suction device for successively removing labels from such stack, the combination with 5 said support and transfer means of means for periodically consolidating the stack by applying a positive pressure to the terminal label within a predetermined area, means for producing an imprint on the terminal label while such stack is so consolidated and within the area of such consolidation, unitary means for periodically engaging a surface of said imprinting means during the printing operations of the latter to control the actuation of said stack support, and means for reciprocating said unitary means to engage said imprinting means each time the latter is producing an imprint and while said consolidating means is exerting a consolidating pressure on the stack.

6. In a labeling machine of the type which comprises a support for a stack of labels and constructed and arranged to be periodically actuated to restore the terminal label of the stack to a predetermined position, and transfer means including a suction device for successively removing labels from such stack, the combination with 20 said support and transfer means of means for periodically consolidating the stack by applying a positive pressure to the terminal label within a predetermined area and producing an imprint on the terminal label while such stack is so consolidated and within the area of such consolidation, unitary means for periodically engaging a surface of said consolidating and imprinting means during the stack consolidating and printing operations of the latter to control the actuation of said stack support, and means for reciprocating said unitary means to engage said consolidating and imprinting means each time the latter is exerting a consolidating pressure on the stack and at the moment said consolidating and imprinting means is producing an imprint on the terminal label.
